UNITED STATES PATENT OFFICE.

FRANK B. ELLS, OF HUTCHINSON, MINNESOTA.

VALVE-GEAR FOR EXPLOSIVE-ENGINES.

No. 823,039.

Specification of Letters Patent.

Patented June 12, 1906.

Application filed July 26, 1904. Serial No. 217,917.

To all whom it may concern:

Be it known that I, FRANK B. ELLS, a citizen of the United States, residing at Hutchinson, in the county of McLeod and State of Minnesota, have invented certain new and useful Improvements in Valve-Gear for Explosive-Engines; and I do hereby declare the following to be a full, clear, and exact description of the invention, such as will enable others skilled in the art to which it appertains to make and use the same.

My invention relates to explosive-engines, and has for its object to improve the same in the several particulars hereinafter noted.

15 The invention consists of the novel devices and combinations of devices hereinafter described, and defined in the claims.

20 In the accompanying drawings, which illustrate my invention, like characters indicate like parts throughout the several views.

Figure 1 is a plan view showing an explosive-engine of the four-cycle type having the several features of my invention applied thereto. Fig. 2 is a view principally in side 25 elevation, but with some parts sectioned and with others broken away, illustrating the parts shown in Fig. 1. Fig. 3 is a detail in section, illustrating on a larger scale than in the other views the construction of the 30 pump-plunger. Fig. 4 is a view corresponding to Fig. 2, but illustrating different positions of the parts; and Fig. 5 is a section on the line $x^1 x^2$ of Fig. 4.

35 The numeral 1 indicates the base, the numeral 2 the cylinder, the numeral 3 the engine crank-shaft, the numeral 4 the fly-wheel, and the numeral 5 the crank-rod, of an explosive-engine of the four-cycle type.

Air is drawn into the cylinder through a 40 delivery-pipe 6, which, as shown, leads from the engine-base 1. The usual valve 7 controls the admission of air into the cylinder from the pipe 6, the said valve being one which will open under suction from within 45 the cylinder, but will close under the force of an explosion.

The numeral 8 indicates the stem of the exhaust-valve, which is of the usual construction, and is subject to a spring 9, which causes 50 said valve to automatically close. This exhaust-valve when pressed inward opens up an exhaust-port 10, extending from the cylinder, as shown in Fig. 1.

A sparking device of the usual construction is employed, and for the purposes of this 55 case it is only necessary to state that the

movable member of the pair of electrodes has a projecting trunnion 11, to which is secured a short arm 12, that is subject to a spring-pressed bolt 13, which bolt is mounted to 60 slide through said arm 12 and through a lug projection of a bracket 14, secured to the side of the cylinder-casting 2. A collar 15 on the bolt 13 normally presses against the arm 12. To the projecting end of the bolt 13 is pivoted 65 a short arm 16, which in turn is pivoted at 17 to the bracket 14. To the depending end of said arm 16 is loosely pivoted a bevel-nosed gravity-held dog 18. A coiled spring 20 on the bolt 13 reacts against the bearing-lug of 70 the bracket 14 and against the collar 15 of said bolt. A coiled spring 21 on said bolt between the arms 12 and 16 yieldingly holds the former against the collar 15.

Interposed in the air-delivery pipe 6 is a 75 pump of novel construction, and which, as shown, comprises a cylindrical casing 22, which is divided into upper and lower compartments 23 and 24. The upper compartment 23 constitutes a part of the air-delivery 80 passage through the pipe 6. The lower compartment 24 is kept filled, approximately to a constant level, with gasoline, which may be supplied thereto from any suitable source and by any suitable means through an ordinary pipe 25. A pump piston or plunger 26 works vertically through the upper walls of the oil-chamber 24 and upper compartment 23 and at its lower end is bifurcated at 27 to afford a seat for a small oil-cup 28, which is 90 pivoted to the lower portion of said piston. This pivoted oil-cup at one side has an arm 29, which when the piston 26 is lowered, as shown in Fig. 2, engages the flanged piston- 95 passage 24^a of the oil-compartment 24 and holds the said cup in an upright position. When, however, the pump-piston is raised, as shown in Fig. 4, and the pivoted cup is carried into the upper compartment 23, the said arm 29 overbalances said cup and causes the 100 same to tip over and deposit the oil carried thereby into the air-supply passage to the cylinder. Under the downward movement of the piston 26 the arm 29 will of course again turn the cup 28 into an upright position. At its upper end the piston 26 is connected by a short link 30 to one arm of a bell-crank 31, which bell-crank is pivotally mounted on a stud 32, projected from one side of the cylinder 2. Projecting from the same 105 side of the cylinder in close proximity to the stud 32 is another but heavier stud 33; and

110

mounted on this stud is an oscillating arm 34, the free end of which is connected by an eccentric-rod 35 to an eccentric 36, carried by the engine crank-shaft 3. This oscillating arm 34 carries a tappet-arm 37, the end of which, under a rearward movement of said arm 34, engages the cam end of the dog 18, presses the same downward against the stop-lug 19 of the arm 16 and forces said arm, the plunger 20, and the arm 12 of the movable electrode toward the left with respect to Fig. 2. This movement of the arm 12, it may be here stated, forces the movable electrode against the fixed electrode of the electric igniter, and the spark is produced in the usual way by the separation of the electrodes, which takes place when the tappet 37 passes below the beveled end of the dog 18. Under a movement of the arm 34 forward toward the right with respect to Figs. 2 and 4 the dog 18 freely rises to permit the tappet 37 to pass.

An oscillating lever 38, which, as shown, is curved, is pivotally connected at its upper end to the oscillating arm 34 and at its lower end is connected by a link 39 to the depending arm of the bell-crank 31. Loosely mounted on the stud 33 outward of the arm 34 is a ratchet-wheel 40, which carries a plurality of radially and laterally projecting fulcrum-lugs 41, which are adapted to be engaged, as presently described, by the intermediate portion 38^a of the lever 38. The oscillating arm 34 carries a driving-pawl 42, that engages the teeth of the ratchet 40. A spring-pressed retaining-pawl 43, which, as shown, is pivoted on the stud 32, operates on the ratchet-wheel 40 to prevent backward rotations thereof. As shown, the ratchet-wheel 40 has eight teeth and four fulcrum-lugs 41.

With the construction described it is evident that the arm 34 will be given one complete operation for each complete rotation of the crank-shaft. The stroke of said arm is such that for each rotation of the crank-shaft the driving-pawl 42 will move the ratchet-wheel 40 a step of movement equal to one tooth—to wit, one-eighth of a rotation. The lower arm of the bell-crank 31 is connected by a rod 44 to one end of a lever 45, pivoted to a bracket 46 with its free end pressing against the projecting end of the exhaust-valve stem 8. The bracket 46, as shown, is rigidly attached to the head of the cylinder 2.

In the position of the parts shown in Fig. 2 one of the fulcrum-lugs 41 stands in position for engagement with the intermediate bearing-portion 38^a of the lever 38, so that the arm 34, being then given a movement toward the right, said lever 38 will be rocked on the said fulcrum-lug and its lower end will be caused to move toward the left, and thereby through the connections described positively force the exhaust-valve inward into an open position and the pump-piston 26 downward

into the position shown in Fig. 2. Under the next rotation of the crank-shaft the ratchet-wheel 40 will be given one step of movement which will carry the space between two of the fulcrum-lugs 41 into line with the bearing-surface 38^a of the lever 38, so that the said lever, under the movement of the arm 34 toward the right, will find no fulcrum over which to rock, and hence will simply move pivotally on the link 39 and will not operate either the exhaust-valve nor the pump-piston.

The upper end of the pump-piston 26 affords a lock-shoulder with which engages one arm of a two-armed lock 47, the shaft of which is mounted in a bearing 48 on the cylinder 2, and the upper arm of which, as shown, is yieldingly pressed outward by a spring 49. (Shown in Fig. 1.) Each time the pump-piston 26 is forced downward into the position shown in Fig. 2 the lower arm of the lock 47 engages with the upper end of said piston, and thereby locks the same in its lowered position and locks the exhaust-valve in open position. This lock is adapted to be released by an automatic governor, a suitable form of which is illustrated in the drawings.

The governor, as shown, is in the form of a weighted arm 50, which is pivoted to and carried by the eccentric-rod 35, and is provided with an arm projection 51, the lower end of which terminates in a depending trip-cam 52 and the upper end of which terminates in a perforated lug 53, that overlies the eccentric-rod 35. Said rod 35 carries a vertically-projected bolt 54, that projects through the lug 53 and on its screw-threaded upper end is provided with a nut 55. On the bolt 54 are a pair of coiled springs 56 and 57, the former of which is compressed between the nut 55 and the lug 53 and the latter of which is compressed between said lug and the eccentric-rod 35. These two springs operating on the governor hold the same in such position that under normal speed the trip-cam 52 will travel such a course that under the movement of said cam downward and toward the left it will engage with a boss 58 on the upper arm of the lock 47, thereby forcing said arm inward and causing the lower arm of said lock to release the pump-piston 26. When this release of the pump-piston takes place, the spring 9 becomes operative to quickly close the exhaust-valve and to quickly throw the pump-piston upward, thereby delivering the gasoline or explosive liquid into the air-supply pipe with a dashing action, which greatly aids the vaporization thereof.

Whenever the speed of the engine exceeds a predetermined limit, which limit may be varied by adjustments of the nut 55, the weighted arm 50 under downward movement toward the left will so overcome the spring 56 that the trip-cam 52 will be caused to travel above and clear of the boss 58 of the

upper arm of the lock 47, thereby leaving the pump-piston in a locked and lowered position and the exhaust-valve locked in an open position until the speed of the engine is again 5 reduced below the set limit.

The practicability of the device has been demonstrated in practice. It will of course be understood that the construction illustrated in the drawings is capable of modification 10 within the scope of my invention as herein set forth and claimed.

What I claim, and desire to secure by Letters Patent of the United States, is as follows:

- 15 1. In an explosive-engine, having an exhaust-valve, fuel-oil-supply device, an engine-driven lever operatively connected to said exhaust-valve and to said fuel-oil-supply device, and a shifting fulcrum for said lever, normally disconnected therefrom, operated by the engine and arranged to be thrown into action on said lever once for each two rotations of the engine crank-shaft, substantially as described.
- 20 2. In a valve-gear for explosive-engines, means for operating the exhaust-valve thereof, comprising a lever operatively connected

to the exhaust-valve and to an engine-driven part, and a shifting fulcrum for said lever, normally disconnected therefrom, operated 30 by the engine and arranged to be thrown into action on said lever once for each two rotations of the engine crank-shaft, substantially as described.

3. In a four-cycle explosive-engine, the 35 combination with an oscillating arm, driven from the engine crank-shaft, a ratchet-wheel mounted to rotate at the pivot of said arm and carrying a plurality of projecting fulcrum-lugs, a pawl carried by said arm for action on 40 said ratchet-wheel, and an oscillating lever pivoted at one end to said oscillating arm, operatively connected at its other end to the exhaust-valve of the engine, and subject, at its intermediate portion, to said fulcrum-lugs, which lugs are brought into action in 45 succession, once for each two rotations of the engine-crank.

In testimony whereof I affix my signature in presence of two witnesses.

FRANK B. ELLS.
